ROPE SLING

Robert F. Joy, Bethlehem, Pa., assignor to
Bethlehem Steel Company, a corporation of
Pennsylvania

Application February 29, 1944, Serial No. 524,497

16 Claims. (Cl. 87—8)

1
This application is a continuation in part of my co-pending application Serial No. 459,155, filed September 21, 1942, now Patent No. 2,359,424, covering Improvements in a rope sling.

My invention relates to rope slings and to a method of making them.

One of the objects of my invention is to provide a method of forming a wire rope sling from an endless unit.

Another object of my invention is to provide a method of forming a multi-part wire rope sling from a wire rope strand spliced to constitute an endless unit.

Another object of the invention is to provide a sling of great lifting capacity and high tensile strength.

Another object of my invention is to provide a non-spinning, non-kinking sling which has great flexibility.

The novel features of my invention will be more fully understood from the following specification and claims, taken with the drawings, in which:

Figure 1 is a plan view showing diagrammatically a rope folded preparatory to interweaving a six part sling by my novel method;

Figs. 2, 3 and 4 are plan views showing diagrammatically the steps of my novel method of interweaving a six part sling;

Fig. 5 is a plan view of a section of a six part sling made in accordance with my invention;

Fig. 6 is an end view of the six part sling shown in Fig. 5;

Fig. 7 is a plan view showing diagrammatically a rope folded preparatory to interweaving an eight part sling by my novel method;

Figs. 8, 9, 10, 11, 12, 13 and 14 are plan views showing diagrammatically the steps of my novel method of interweaving an eight part sling; and

Fig. 15 is a plan view of a section of an eight part sling made in accordance with my invention.

Referring now more particularly to Figs. 1 to 4, inclusive, of the drawings, I show a rope in the various stages of being interwoven into a six part sling. An elementary strand 20 is folded upon itself to provide six body members 21, 22, 23, 24, 25, 26 and three loops 27, 28, 29, at one end, and two loops 30 and 31 and two free ends 32 and 33. The free ends 32 and 33 can be spliced together as shown in dotted lines in Fig. 1 either before the start or at the finish of the making of the sling. Seizing is applied preferably to the end having the two free ends or splice, or instead of seizing, the spliced end may be passed over an eye-forming block. Interweaving is started by rotating center loop 28 in a clockwise direction, body

2
member 23 overlaying body member 24, and passing it through right outside loop 29 as shown in Fig. 2. This step positions loop 29 in the center whereupon it is rotated in a counter-clockwise direction, body member 26 overlaying body member 25, and passed through left outside loop 27 as shown in Fig. 3. This step positions loop 27 in the center whereupon it is rotated in a clockwise direction, body member 21 overlaying body member 22, and passed through right outside loop 28 as shown in Fig. 4. Each loop as it becomes the center loop is twisted either in a clockwise or counter-clockwise direction, whichever is opposite to the twist imparted in the previous operation, and is passed either through the loop to the right or left, whichever direction is opposite to the direction of passing of the previous operation. This procedure is continued until just enough of the loops remain to form eyes.

Referring now more particularly to Figs. 7 to 14, inclusive, of the drawings, I show a rope in the various stages of being interwoven into an eight part sling. An elementary strand 34 is folded upon itself to provide eight body members 35, 36, 37, 38, 39, 40, 41 and 42 with four loops 43, 44, 45, and 46 at one end, and three loops 47, 48 and 49 and two free ends 50 and 51 at the other end. It should be noted that no twisting of the separate loops is employed prior to interweaving. The free ends 50 and 51 can be spliced together as shown in dotted lines in Fig. 7 either before the start or at the finish of the making of the sling. Temporary seizing may be applied preferably near the end having the two free ends 50 and 51 or splice to position the loops in their proper relationship. Instead of applying seizing, the splice end may be passed over an eye-forming block and secured thereto by means of wires or other locking means which pass through holes in the block. Preferably, interweaving is started by twisting the right center loop 45 in a clockwise direction so that body member 39 overlays body member 40 and then passing loop 45 through the outer right-hand loop 46. This step is shown in Fig. 8, loop 46 being now the right center loop. Loop 46 is then given a twist in a counter-clockwise direction, body member 42 overlaying body member 41, and is passed through the left center loop 44. This step is shown in Fig. 9, loop 43 being now the left center loop. Loop 46 is then given a twist in a counter-clockwise direction, body member 41 overlaying body member 42, and outer left-hand loop 43 is given a twist in a clockwise direction, body member 35 overlaying body member 36, and loop 43 is passed through loop 46, loop 46 now

being the outer left-hand loop, this step being shown in Fig. 10. It will be noted that loop 46, the original outer right-hand loop has straddled the first loop to its left, passed through the next loop, and straddled the last loop to become the outer left hand loop. This procedure is repeated, that is, the outer right-hand loop is alternately passed over and through the adjacent loops until it straddles the oppositely twisted left outside loop when it becomes itself the outer left-hand loop, a counter-clockwise twist being imparted to it after it passes over the first center loop and after it passes through the second center loop. It will be seen, upon reference to the drawings, that the body members of the loops are alternately divided and paired by the other loops and that after being divided and prior to being paired each loop is given a twist; and that the twist is in one direction when the loop travels from right to left and is in the other direction when the loop travels from left to right. This procedure of twisting serves to lock the loops one within the other and by reversing the twist there will be no tendency in the finished sling to twist upon itself and the loops will remain free of twist throughout weaving. This process is continued until a point has been reached where just enough of the loops remain to form eyes. The end loops or eyes are fastened together preferably with fine wire serving which binds them in a compact form and makes a single loop into which a thimble may be inserted.

My method of forming slings by passing a loop through an adjacent loop will produce a sling in which each member of all loops will be effectively locked against a member of an adjacent loop.

While I have shown my invention in a plurality of forms, it will be obvious to those skilled in the art that it is not so limited, but is susceptible of various other changes and modifications without departing from the spirit thereof, and I desire, therefore, that only such limitations shall be placed thereon as are imposed by the prior art or as are specifically set forth in the appended claims.

Having thus described my invention, what I claim as new and desire to secure by Letters Patent is:

1. The method of producing a multi-part flexible sling which comprises folding an elementary strand to form a plurality of loops, passing a first loop through a second loop, and then passing said second loop through a third loop.

2. The method of producing a multi-part flexible sling which comprises folding an elementary strand to form an outside loop, a center loop and another outside loop, passing said center loop through said first mentioned outside loop, and then passing said first mentioned outside loop through said other outside loop.

3. The method of producing a multi-part flexible sling which comprises folding an elementary strand to form a plurality of loops, twisting a loop and passing it through a second loop, twisting said second loop in a direction opposite to that of said first mentioned loop and passing said second loop through a third loop.

4. The method of producing a multi-part flexible sling which comprises folding an elementary strand to form a left outside loop, a center loop and a right outside loop, twisting said center loop clockwise and passing it through said right outside loop, twisting said right outside loop counter-clockwise and passing it through said

left outside loop, and twisting said left outside loop clockwise and passing it through said center loop.

5. The method of producing a multi-part flexible sling which comprises folding an elementary strand to form a left outside loop, a center loop and a right outside loop, twisting said center loop clockwise and passing it through said right outside loop, twisting said right outside loop and passing it through said left outside loop, and twisting said left outside loop in a direction opposite to that of said right outside loop and passing said left outside loop through said center loop.

6. The method of producing a multi-part flexible sling which comprises folding an elementary strand to form a left outside loop, a left center loop, a right center loop, and a right outside loop, passing said right center loop through said right outside loop, passing said right outside loop through said left center loop, and passing said left outside loop through said right outside loop.

7. The method of producing a multi-part flexible sling which comprises folding an elementary strand to form a left outside loop, a left center loop, a right center loop, and a right outside loop, twisting said right center loop and passing it through said right outside loop, twisting said right outside loop and passing it through said left center loop, and twisting said left outside loop and passing it through said right outside loop.

8. The method of producing a multi-part flexible sling which comprises folding an elementary strand to form a left outside loop, a left center loop, a right center loop, and a right outside loop, twisting said right center loop in a clockwise direction and passing it through said right outside loop, twisting said right outside loop in a counter-clockwise direction and passing it through said left center loop, and twisting said left outside loop in a clockwise direction and passing it through said right outside loop.

9. A flexible multi-part sling formed from a single elementary strand, said sling comprising a plurality of interwoven loops, each of said loops comprising two body members alternately divided and paired by body members of adjacent loops alternately disposed intermediate said divided portions and around said paired portions.

10. A flexible multi-part sling formed from a single elementary strand, said sling comprising three interwoven loops, each of said loops having two body members alternately divided and paired by the body members of adjacent loops.

11. A flexible multi-part sling formed from a single elementary strand, said sling comprising four interwoven loops, each of said loops having two body members alternately divided and paired by the body members of adjacent loops.

12. A flexible multi-part sling formed from a single elementary strand, said sling comprising a plurality of interwoven loops, each of said loops comprising two body members alternately divided and paired by body members of adjacent loops alternately disposed intermediate said divided portions and around said paired portions and said body members having a twisted portion adjacent said divided portion.

13. A flexible multi-part sling formed from a single elementary strand, said sling comprising three interwoven loops, each of said loops comprising two body members having alternate divided portions and paired portions, body members of adjacent loops passing through said divided portions and passing around said paired

portions and said body members having a twisted portion adjacent said divided portion.

14. A flexible multi-part sling formed from a single elementary strand, said sling comprising four interwoven loops, each of said loops comprising two body members alternately divided and paired by body members of adjacent loops, each of the adjacent loops alternately passing through a divided portion of the body members of a loop and around a paired portion of the body members of a succeeding loop, and said body members having a twisted portion adjacent each of said divided portions.

15. The method of producing a multi-part flexible sling comprising folding an elementary

strand to form a series of loops, said series of loops comprising outside and center loops, then passing a center loop through one of said outside loops, and passing the latter outside loop through another of said series of loops.

16. The method of producing a multi-part flexible sling comprising folding an elementary strand to form a series of loops, said series of loops comprising outside and center loops, then twisting a center loop and passing it through one of said outside loops, and twisting the latter outside loop and passing it through another of said series of loops.
